(57) **CLAIM**

The ornamental design for an image display apparatus, as shown and described.

DESCRIPTION

FIG. 1 is a front and right side perspective view of an image display apparatus, showing our new design;

FIG. 2 is a rear, top and left side perspective thereof;

FIG. 3 is a front elevational view thereof;

FIG. 4 is a rear elevational view thereof;

FIG. 5 is a top plan view thereof; and

FIG. 6 is a bottom plan view thereof.

FIG. 7 is a right side elevational view thereof; and,

FIG. 8 is a left side elevational view thereof.

The broken line showing of the remainder of the image display apparatus is for illustrative purposes only and forms no part of the claimed design.
